Primary Examiner — Sheryl Lane(74) *Attorney, Agent, or Firm* — Richard John Bartz(57) **CLAIM**

The ornamental design of the cutting blade, as shown and described.

DESCRIPTION

FIG. 1 is a front elevational view of a first embodiment of the cutting blade of my new design;
 FIG. 2 is a top plan view thereof;
 FIG. 3 is a bottom plan view thereof;
 FIG. 4 is a side elevational view of the right side thereof;
 FIG. 5 is a side elevational view of the left side thereof;
 FIG. 6 is a back elevational view thereof;
 FIG. 7 is a sectional view taken along line 7-7 of FIG. 1;
 FIG. 8 is a sectional view taken along line 8-8 of FIG. 1;
 FIG. 9 is a front elevational view of a second embodiment of the cutting blade of my new design;
 FIG. 10 is a top plan view of FIG. 9;
 FIG. 11 is a bottom plan view of FIG. 9;
 FIG. 12 is a side elevational view of the right side of FIG. 9;
 FIG. 13 is a side elevational view of the left side of FIG. 9;
 FIG. 14 is a back elevational view of FIG. 9;
 FIG. 15 is a sectional view taken along line 15-15 of FIG. 9; and,
 FIG. 16 is a sectional view taken along line 16-16 of FIG. 9.
